E. CRISPIN

APPARATUS FOR MAKING BUILDING UNITS

Filed July 26, 1924

FIG. 7.

FIG. 9.

INVENTOR,

EDWARD CRISPIN.

By Martin O. Smith Atty.

UNITED STATES PATENT OFFICE.

EDWARD CRISPIN, OF LOS ANGELES, CALIFORNIA.

APPARATUS FOR MAKING BUILDING UNITS.

Application filed July 26, 1924. Serial No. 728,444.

My invention relates to new and useful building articles and method of producing same, the principal objects of my invention being to produce, by a relatively simple and easily practiced method, finished building articles that may be economically and advantageously employed in interior and exterior work, in new and old building structures to give the same a new appearance. My finished building articles are especially adapted for use as coverings for walls, roofs, ceilings, store fronts, mantels, fireplaces and the like.

Further objects of my invention are to provide finished building articles that represent or imitate brickwork of any desired size, that are relatively light in weight, strong and durable, both fire and waterproof, not affected by heat, the sun's rays or dampness and, further, to provide building articles of the character referred to that may be sawed or nailed without splitting, which will not warp, shrink or swell, which may be readily handled, easily and quickly made and applied, and which do not require painting or similar finished operations.

With the foregoing and other objects in view, my invention consists in certain novel features of construction and arrangement of parts that will be hereinafter more fully described and claimed and illustrated in the accompanying drawings, in which:

Figure 1 is a sectional view of the master pattern or slab as the same is produced on a table or like support;

Figure 2 is a sectional view of the master pattern with joint representing grooves formed therein;

Figure 3 is a sectional view of the master pattern showing the surfaces thereof between the joint grooves sanded to produce rough surfaces on the moulds;

Figure 4 is a sectional view showing a mould as the same is produced upon the master pattern;

Figure 5 is a sectional view of the mould in position upon the casting table or support;

Figure 6 is a plan view of the mould in position to receive the plastic material;

Figure 7 is an elevational view showing the means utilized for filling the moulds and the roller that is used for pressing the back ing paper onto the casts;

Figure 8 is a perspective view of a foun-

tain roller that is used for coloring the joint 55 representing grooves of the finished casts;

Figure 9 is a vertical section taken through the horizontal joint between two adjacent panel members showing the arrangement of the backing strips at said joints; 60

Figure 10 is a detail section showing a joint strip that is applied to the rear sides of the casts for connecting the vertical joints thereof;

Figure 11 is an elevational view of a tuck 65 pointer's brush that may be used for coloring the joint representing grooves in the finished casts.

In carrying out my method for the production of building articles having one surface 70 formed so as to represent brick work, a model pattern is produced by forming, on a suitable base 10, having an oiled straight flat surface, a plate or slab 11 of suitable material such as plaster of Paris. 75

This pattern plate may be of any desired size, for instance, three feet square and an inch in thickness and to reinforce and strengthen this plate, burlap 12 or suitable fibrous material is embedded therein. 80

When this plate is set and hard, it is turned over and grooves, such as 14, are formed in the smooth surface, and which grooves are arranged after the manner of grooves or joints in brick or stone work. 85

After this plate is thoroughly dry, its grooved surface is coated with thin shellac and after the latter has dried, a coat of paint is applied to said grooved surface. To produce rough surfaces on the finished casts, a heavy coat of drying oil paint or varnish is applied to the surface of the plate, but not to the surfaces of the grooves, and these painted or varnished surfaces are sanded with sand or gravel, or they may be coated with clay or analogous material and modeled with a comb or like tool. If desired, the casts may be further reinforced by embedding in the bodies thereof between their front and rear surfaces a section or sections of woven or fibrous material 16 such as burlap. 95

When dry, the surface thus treated is dusted off and painted with a soft brush without rubbing, and stippled and this treatment will fasten the sand or gravel on the surface. When this model is thoroughly dry, a ledge is formed around the model about one inch in height and this ledge is 100 105

fastened so as to hold the plastic mass on the surface.

Before the mould casts are made the surface of the model is coated with casting oil or grease. A plastic material such as plaster of Paris or magnesite composition is applied to the prepared surface of the model and a backing or burlap or paper such as 17 is placed over the plastic material and 10 smoothed straight with a trowel or straight edge. When the plastic material forming the mould cast is set and hard, said cast is then lifted off from the model and removed.

A sufficient number of mould casts such as 15 are made to form as long a mould as is desired. The mould casts thus produced are fitted together on a suitable level support or table about three and one-half or four feet wide, the most desirable arrangement being 20 in making a long main mould, to place the mould casts in a length of from sixty to one hundred feet and then dividing the same into suitable sections. On each long side of the main mould, narrow ledges of wood or 25 metal 19 about one inch wide and from one-half to three-eighths of an inch higher than the mould, are fastened to the supporting table and the projecting portions of these ledges govern the thickness of the finished 30 casts. These ledges hold the plastic material on the mould surface and also provide tracks for a roller.

Each section of the main mould is connected to the support or table by means of 35 hinges 18 in order that each section may be swung into a vertical position to facilitate removal of the finished cast from the mould.

On one side of each section of the main mould, small strips 20 of thin sheet steel 40 having sharp beveled upper edges that are arranged at the same height as the projecting ledges are arranged to form a cutting edge. These thin metal sections divide the casting material that is placed in the main 45 mould. Adapted to cooperate with this cutting edge is a similar plate 21 of corresponding shape that is carried by a bar 22 having a handle 23 on its front end. The rear end of this bar is provided with a hook 24 that 50 is adapted to engage in a loop 25 on each section back of the main mould and which is secured to the support or table. On the opposite or front side of the main mould in transverse alignment with the loop 24 is a 55 slotted guide 26 that is adapted to receive the bar 22 when the latter is manipulated to cut and separate the backing that is applied to the back of the cast. As the handle 22 is pressed downward, the parts 20 and 21 60 cooperate in a shear-like manner to separate the finished casts.

The surface of the main mould that is divided in sections is shellacked and painted. When dry, and before the casts are made, 65 the surface of said main mould is coated

with casting oil or grease and when so treated, is ready to receive the plastic mass. Obviously the mould constructed as just described may be formed from other material, for instance, they may be formed from glue, 70 rubber, rubber composition, wood, or glass.

In producing casts that represent brick or stone work, shingles, wall or roof tile, a very satisfactory plastic mass may be made from magnesite 100 per cent, wood pulp, 33 per 75 cent, kieselguhr 10 per cent, all by measure, and these ingredients are mixed with liquid magnesium chloride 22 per cent Baumé so as to produce a dough-like mass that will run when poured into the mold. 80

The plastic mass used in the production of the surface finished casts may be applied to the moulds in any suitable manner, but I prefer to utilize a large container, such as 30, having a pouring spout 31, said container or receptacle being carried by a suitable hanger or support 32, the upper portion of which is mounted to travel freely upon a rail or support 33 that extends lengthwise above the moulds. Thus the entire main mould may be readily filled by proper manipulation of the container 30. After the moulds have been filled with the plastic mass up to the level of the upper edges of ledges 19, the upper surface of the plastic mass is smoothed off with a plasterer's trowel or straight edge, and from a roll of paper that is known to the trade as "building paper" a backing for the cast is pulled over the plastic mass and arranged so as to overlie the upper or rear ledge 19 but not over the lower or bottom ledge. The ends of this strip of paper are fastened to prevent said paper from slipping, and a roller, such as 35, which weighs approximately twenty-five pounds, is now 100 rolled lengthwise over the main mould, with its ends bearing on ledges 19 to press the paper into intimate contact with the plastic mass and produce a smooth finished surface. This roller is supported by a suitable hanger, 110 such as 36, the upper portion of which is adapted to travel lengthwise over the track 33. 115

When the plastic filling within the main mould has become set, and hard, the cutting bar 22 is used to cut the backing paper and thereby separate the section casts from each other, and to accomplish this separation the hook 24 on the rear end of bar 22 is engaged in loop 25 and said bar is now moved downward so that the blades 21 thereon, cooperate with the corresponding blades 20 at the ends of the section moulds, and thus said blades 20 and 21 effect a shear cut to sever the backing at the ends of each section cast. 120 As bar 22 is lowered to effect this shear cut, it is guided by engagement with the slotted member 26. The same cutting bar is used on each section. After the backing paper on the section casts has been thus cut, the section 125

moulds are swung upon their hinges 18 into vertical position, thereby enabling the casts to be readily removed from the moulds and said casts are now placed on suitable supports.

In order to tint or color different parts of the surface of the casts, the desired colors are dissolved in water and then mixed with some plastic mass and some magnesium and magnesite chloride, and the coloring matter thus produced may be applied to different portions of the finished surfaces of the casts through the use of suitable stencils and brushes.

15 Spotting with colors is accomplished by using a relatively large brush or sponge that is dipped in the liquid color and then sprinkled over the surface of the cast.

In order to color the grooves that represent the joints between the brick representing surfaces, a tuck pointer's brush (see Figure 11) may be used or the color may be applied through the use of a narrow rubber surfaced wheel that receives the coloring matter from a bulb-shaped color container, which latter, when slightly pressed will feed the liquid color to the surface of the wheel (see Figure 8).

In putting up the finished casts, a narrow strip of thin paper that is coated with wet plastic material is placed behind the joints between the casts before they are nailed or fastened by means of plastic material to the structural surface thereby producing air and moisture proof joints.

Where the casts are applied to brick or plastered surfaces, a coat of magnesite plaster is first applied and the casts are pressed onto said plaster before the same is set, and fastened in any suitable manner to hold them in their position until the magnesite plaster is set and hard. Wherever necessary, as, for instance, on ceilings, the casts may be retained in position by suitable framework until the magnesite plaster has become set and hard.

After the casts have been properly applied, as just described, the outer surfaces thereof may be given a washing of thin oil

like gasoline, which will remove dusty spots resulting from contact of the hands in putting up the work.

In the production of ceiling or roof coverings, a plain smooth surface, an ornamental surface, or a surface resembling tiles or shingles may be produced in the same manner as hereinbefore described and with the same plastic composition. Through the use of moulds of glass or moulds having glass surfaces, casts having highly finished or glossy surfaces may be produced.

Thus it will be seen that I have provided a relatively simple, inexpensive and easily practiced method for producing finished building articles of self-hardening plastic material, which latter may be advantageously employed in the surfacing and covering of practically all new and old building structures that will represent brick, stone, mosaic, frieze or cornice work, in fact any ornamental relief work that is adaptable for buildings and the decoration thereof.

Obviously the casts produced in accordance with my invention may be made in various sizes to suit different requirements, but for economy in production, handling and installation it is more advantageous to produce the casts in the larger sizes as they can be cut and fastened in any desired size and shape.

I claim as my invention:

An apparatus for producing finished fire and waterproof building articles comprising a series of separately formed identical sections arranged in a row to form an elongated mold, a support for the entire series of molds, hinges connecting each mold with said support, retaining strips arranged in the side edges of the separate sections, which strips serve as supports for a roller, brackets for receiving and supporting a cutting device arranged in transverse alignment with the joints between the mold sections and a cutting device to engage said brackets when the cast that is formed on the sectional mold is divided.

In testimony whereof I affix my signature.
EDWARD CRISPIN.
